UNITED STATES PATENT OFFICE.

ROBERT E. POWERS, OF MONTREAL, QUEBEC, CANADA, ASSIGNOR, BY DIRECT AND MESNE ASSIGNMENTS, OF ONE-FOURTH TO ALBERT C. MURPHY AND ONE-FOURTH TO JOHN H. ALLEN, BOTH OF NEW YORK, N. Y.

CENTERING DEVICE FOR CAR-COUPINGS.

1,116,626.

Specification of Letters Patent. Patented Nov. 10, 1914.

Application filed October 9, 1903. Serial No. 457,004.

To all whom it may concern:

Be it known that I, ROBERT E. POWERS, of the city of Montreal, in the Province of Quebec and Dominion of Canada, have invented certain new and useful Improvements in Centering Devices for Car-Couplers, and do hereby declare that the following is a full, clear, and exact description of same.

10 My invention relates to improvements in centering devices for car couplers and the main object of the invention is to provide a simple and inexpensive device which will positively keep the couplers of a car in line 15 with the center thereof but which will yield sufficiently to the sway of the cars to prevent breakage.

A further object is to provide a centering device which will be practically frictionless 20 and which will be actuated by the force of gravity.

The couplers at present in use will not couple with the impact of the cars unless the couplers are approximately in line with each 25 other. To prevent the couplers getting too far out of line, their oscillatory movement is very much limited with the result that on sharp curves a great strain is thrown on the couplers and the wheel flanges thrown 30 against the rails thus materially increasing the tractive resistance.

This invention aims to provide means for returning the couplers into line with the center of the car and for maintaining the 35 same in alinement under all ordinary circumstances. Thus the couplers may be allowed a greater oscillatory movement resulting in fewer breakages and less tractive resistance.

10 To accomplish the above objects, I provide a small carriage, located beneath and supporting the coupler member, said carriage being provided with lugs engaging the sides of said member. The carriage travels 15 on a curved track formed in a member which is bolted or otherwise secured to the channels forming the center sill of the car. When the carriage rests on the lowermost 20 portion of the curved track, the coupler member guided thereby will be in line with the center of the car to which it is attached.

The contour of the track will maintain the carriage and coupler at the lowest or central portion of the track, the carriage always returning by gravity to its normal position. 55

In the drawings which illustrate my invention:—Figure 1 shows on the left a front elevation of the device and on the right a sectional view on the line 6—7 of Fig. 2. Fig. 2 is a plan view of the stirrup member. 60 Fig. 3 is a transverse section of the same on the line 8—9 of Fig. 2. Fig. 4 is a plan view of the carriage. Fig. 5 is an end elevation of the carriage.

In the above defined figures, 10 designates 65 the channels which form the center sills of the car and 11 the coupler member. The stirrup member 12, which is shaped substantially as shown in Figs. 1, 2 and 3, is secured between the lower flanges of the channels 10 by means of bolts or rivets 13. The stirrup 12 comprises front, center, and rear vertical, transverse plates 14, 15 and 16, respectively, which are united by vertical, longitudinal side plates 17 integral therewith 75 and terminating in flanges 18, through which the attaching bolts 13 pass. The front and center plates 14 and 15, are united at the top by a horizontal plate 19, integral therewith. The center and rear plates 15 80 and 16 are united at the bottom by a double curved track plate 20, the curves of which are portions of the arcs of two intersecting circles of equal diameter. The member is strengthened by a rib 21, which is located 85 longitudinally in the center thereof. Apertures 22 are formed in the track plate 20 and serve to lighten the member, reduce the frictional contact between it and the other parts of the device, and provide for the escape of 90 cinders, water, etc.

A carriage is located between the coupler 11 and the track plate 20 and supports the former. This carriage comprises a horizontal table 23 having front and rear, transverse, downwardly extending flanges 24 from which depend a plurality of lugs 25 through which the pins 26, carrying the rollers 27, pass. The top of the table 23 is provided at its extremities with curved, upwardly extending, plates 28, stiffened by ribs 29, adapted to engage the sides of the coupler member 100

11, as seen in Fig. 1. The carriage is strengthened by a central longitudinal rib 30.

When assembled, the parts are in the relation shown in Fig. 1, the carriage resting on the track plate 20 and supporting the coupler member 11, normally in line with the car center. When in the center, the weight of the coupler is largely removed from the carriage as the coupler also rests on the top plate 19 of the stirrup. When the swing or sway of the cars or the act of uncoupling, moves the coupler out of line, it carries the carriage with it. The carriage, by reason of the curved track plate 15 on which it travels, is compelled to rise and in its rise raises the coupler with it. It is obvious that this rise is in direct opposition to the force of gravity which will therefore produce a downward movement of the coupler and carriage. This downward movement, owing to the curvature of the track plate, is accompanied by an inward movement, wherefore the coupler is brought into line with the center of the car and normally maintained there, the wheels or rollers of the carriage resting on the lowest portion of the curved track plate.

It will be obvious to those familiar with the art to which this invention relates, that the use of the rollers traveling on a track of minimum area will result in a practically frictionless device in which all the energy developed is devoted to maintaining the coupler in line with the center of the car. It will also be obvious that the device consists of a minimum number of simple parts, not liable to damage which may be standardized and rendered applicable to all cars. It will further be seen that this device will greatly minimize the breakage of couplers in making up trains and while running. By allowing a greater oscillation of the coupler, the

tractive resistance is diminished and the safety of the train increased.

Having thus described my invention what I claim is:—

1. A centering device for couplers comprising a stirrup member fixed to the center sill of the car, a downwardly curved track on said stirrup below the coupler, a carriage supporting the coupler, rollers mounted on the carriage and supporting the same above the track, and curved end plates on said carriage engaging the sides of the coupler, substantially as described. 55

2. A device of the character described, comprising a stirrup having a top coupler-supporting plate, a curved track plate sunk below said top plate, a carriage mounted on rollers superposed on said track plate and adapted to center itself by gravity with respect to the longitudinal axis of the car, and coupler engaging end plates on said carriage, substantially as described. 66

3. A device of the character described comprising the combination with a coupler, of a stirrup having a front plate, a top coupler supporting plate, a track plate below said top plate having a plurality of downwardly curved portions with apertures 70 therein, a carriage superposed on said track plate and adapted to support the coupler, depending flanges on said carriage, rollers mounted between said flanges and traveling on the track plate, and end plates for the 75 carriage adapted to maintain the coupler and carriage in engagement.

In witness whereof I have hereunto set my hand in the presence of two witnesses.

ROBERT E. POWERS.
